Specification for Design.

Patented June 7, 1910.

Application filed March 30, 1909. Serial No. 486,828. Term of patent 14 years.

To all whom it may concern:

Be it known that I, PHILIP J. HANDEL, a citizen of the United States, residing at Meriden, in the county of New Haven and State of Connecticut, have invented a new, original, and ornamental Design for Lamp-Shades, of which the following is a specification, reference being had to the accompanying drawings, forming part thereof.

Figure 1 is a view of one side of a lamp shade showing my design. Fig. 2 is a view of the reverse side of the lamp shade.

The design consists of a lamp shade of spherical form on which there is depicted in relief the continents surrounded by water, the surface of which is represented as being rippled and roughened.

I claim:

The ornamental design for a lamp shade as shown and described.

PHILIP J. HANDEL.
